Pierre Barnes
ATTORNEY

UNITED STATES PATENT OFFICE.

WILLIAM H. DAVIDSON, OF SEATTLE, WASHINGTON.

OIL BURNER.

1,414,725.

Specification of Letters Patent.

Patented May 2, 1922.

Application filed April 9, 1920. Serial No. 372,469.

To all whom it may concern:

Be it known that I, WILLIAM H. DAVIDSON, citizen of the United States, residing at Seattle, in the county of King and State of Washington, have invented certain new and useful improvements in Oil Burners, of which the following is a specification.

This invention relates to oil burners for use, more especially, in the fire boxes of stoves, furnaces and boilers.

The primary object of my invention is to produce a burner of this type which will be of simple and inexpensive construction, and efficient in operation.

Another object is to provide a burner which will afford a better mixture of the volatilized oil and air to insure a complete combustion of the fuel.

A further object of the invention is to provide an oil burner of separable parts which are readily detachable for cleaning.

The invention consists in the novel construction, arrangement and combination of parts as will be hereinafter described and claimed.

In the accompanying drawings,

Figure 1 is a view partly in plan and partly in horizontal section of an oil burner embodying my invention. Fig. 2 is a front elevational view of the same, one of the burner heads being shown in vertical transverse section.

Figs. 3 and 4 are sectional views through 3-3 and 4-4 of Fig. 1. Fig. 5 is a detail longitudinal sectional view to an enlarged scale of the gas discharge nozzle and retort tube.

In carrying out my invention I provide a manifold 10 having a cylindrical chamber 11 extending substantially its entire length and from the ends of which are upwardly extending tubular branches or hubs 12. Said hubs are formed with tapering upper extremities which fit into correspondingly shaped sockets provided in bosses 13 of circular burner heads, indicated generally by 14.

Each of said heads is composed of a base member 15 and a cap member 16 having interfitting flange and groove connections 17 in their peripheral walls.

The cap member 16 of a burner head is formed with an annular outer portion 18 of an arcuate shape in transverse section, as shown in Fig. 2, and affording a central cavity 18¹. Such annular portion 18 is slotted radially of the head to provide a plu-

rality of kerfs 19 through which combustible gas is emitted from the burner chamber 20 to be consumed in a series of flames of substantially fish-tail shapes.

The heads are readily removed by lifting the same from the respective hubs 12 and the members of each head are separably coupled as by means of screw bolts 21.

At or near its midlength the manifold 10 is provided at opposite sides with inlet and outlet openings 22 and 23, respectively.

The opening 22 communicates with a chamber 24 formed in the manifold structure and serves as a passage extending longitudinally of the manifold and is connected at one end of the latter to the leg 25 of a substantially U-shaped pipe 26 whose other leg 27 is tapered and engages in the side outlet 28 of a hollow cylindrical attachment 29.

The cylindrical part or body of said attachment has a passage 30 extending its entire length and is preferably arranged to have its axis vertical. Diametrically opposite the outlet 28, said attachment is provided with an opening 31 to receive a gas nozzle 32, which is secured by means of a coupling 33 to the end of a horizontal tube 34 which serves as the vaporizer or retort member of the burner.

The tube 34, or retort as hereinafter designated, extends in parallel relation, or nearly so, with the manifold 10 and is connected by means of a T-fitting 35 with a pipe 36 leading from an oil supply or reservoir, not shown. 37 represents a rod extending axially through said retort and has a conical extremity 38 (Fig. 5) to constitute a needle valve, so called, with respect to an orifice 39 provided in the outer end of the coupling 33.

As shown in Fig. 5, the orifice 39 has a plurality of branch ducts 40 leading into a cavity 41 provided interiorly of the nozzle 32, the latter being provided with a single outlet 42 which is disposed to direct the generated gas diametrically across the passage 30 and axially with respect to the pipe leg 27.

Subjacent to the retort is an auxiliary burner head 43 which is connected intermediate its length by a tubular bracket element 44 with the aforesaid manifold 10. The upper wall of the head 43 is formed with a central ridge 45 between two grooves 46, said ridge being provided with transverse slots 47. Suitable supporting means,

such as legs 48, are provided for the manifold which, in turn, supports the various parts above referred to.

To operate the device, the valve 38 is first 5 adjusted to close the openings 39 and 40 at the discharge end of the retort 34.

A small quantity of waste soaked in oil is then placed in the grooves 46 and burnt to effect the heating of the retort 34 into which 10 oil is then fed through the pipe 36. The oil admitted into the retort and subjected to heat becomes volatilized into a gas which, upon opening the valve is discharged across passage 30 into the pipe leg 27 to mix with 15 air entering the pipe in converging streams from the upper and lower ends of the passage 30. Thence the oil and air travel together through the curved pipe 26, and manifold passage 24 into the middle of the 20 reservoir chamber 11.

By taking the above tortuous course the oil and air become thoroughly mixed when introduced into chamber 11. The mixture is discharged from the latter through the 25 opening 23 into the auxiliary head 43 and also through the hubs 12 into the main burner heads 14 whence the mixture escapes through the respective slots 47 and 19.

The burning waste above mentioned ignites the combustible gas discharging from the auxiliary head 43, and the flames from the latter ignite, in turn, the gas discharged from the main heads 14.

With the burner thus operating the gene-

ration of gas in the retort is continued 35 through the instrumentality of the auxiliary burner-head for the purpose of supplying the main burner-heads 14 whereby heat may be effectually and economically produced.

What I claim is:

In an oil-burner, the combination of a manifold having a reservoir, burner heads communicating with the opposite ends of said reservoir, a supplementary burner head disposed at one side of said manifold and 40 communicatively connected with the reservoir at the midlength thereof, a passage at the side of the manifold and having communicative connection with the reservoir opposite to the connection of the same with the said supplementary head, an air receiving member disposed adjacent to one end of the latter, a substantially U-shaped pipe connecting said member with said passage, a retort-tube provided above said supplementary head, an oil supply pipe connected to one end of the retort-tube, a discharge nozzle for the other end of the retort-tube and extending into said member, and a valve in said nozzle for regulating the discharge of gas from the retort-tube into the air receiving member.

Signed at Seattle, this 3rd day of April 1920.

WILLIAM H. DAVIDSON.
